UNITED STATES PATENT OFFICE.

GEORGE H. FREERS, OF INDIANAPOLIS, INDIANA.

DESIGN FOR A FACEPLATE FOR A TAIL LAMP.

Application filed October 9, 1925. Serial No. 15,074. Term of patent 14 years.

To all whom it may concern:

Be it known that I, GEORGE H. FREERS, a citizen of the United States, residing at Indianapolis, in the county of Marion and State of Indiana, have invented a new, original, and ornamental Design for a Faceplate for Tail Lamps, of which the following is a specification, reference being had to the accompanying drawing, forming part hereof.

The figure is an elevation of the face of an automobile tail lamp, showing my new design.

I claim:

The ornamental design for a faceplate for a tail lamp as shown.

In witness whereof, I have hereunto set my hand.

GEORGE H. FREERS.
